[57] CLAIM

The ornamental design for a personal radio communication device, as shown and described.

DESCRIPTION

FIG. 1 is a front, elevational view of a personal radio communication device showing our new design;
FIG. 2 is a rear elevational view thereof;
FIG. 3 is a top plan view thereof;
FIG. 4 is a left side elevational view thereof;
FIG. 5 is a right side elevational view thereof; and,
FIG. 6 is a bottom plan view thereof.

The broken lines showing the outlines of key buttons on the front and on the left side thereof are for illustrative purposes only and form no part of the claimed design.

*FIG. 3**FIG. 2**FIG. 1**FIG. 6**FIG. 4**FIG. 5*
